(57) **CLAIM**

The ornamental design for a building cladding attachment device, as shown and described.

DESCRIPTION

FIG. 1 is a front left top perspective view of a building cladding attachment device showing an embodiment of our new design;

FIG. 2 is a front right bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded front left top perspective view thereof; and,

FIG. 10 is an exploded front right bottom perspective view thereof.

The dashed broken lines shown in the Figures represent portions of the building cladding attachment device that form no part of the claimed design. The dot-dash broken lines define the bounds of the claimed design and form no part thereof. The appearance of any portion of the building

(Continued)

cladding attachment device between the break lines forms no part of the claimed design.
